US00D772324S

(12) **United States Design Patent** (10) **Patent No.:** **US D772,324 S**
Bennermark et al. (45) **Date of Patent:** **** Nov. 22, 2016**

(54) **MONITORING CAMERA**

(71) Applicant: **AXIS AB**, Lund (SE)

(72) Inventors: **Petra Bennermark**, Lomma (SE);
Johan Hagg, Lund (SE); **Olaf Hoyer**,
Lund (SE); **Lars-Ola Larsson**, Malmo
(SE); **Magnus Sjoberg**, Lomma (SE);
Mathias Walter, Arlov (SE)

(73) Assignee: **AXIS AB**, Lund (SE)

(**) Term: **15 Years**

(21) Appl. No.: **29/532,550**

(22) Filed: **Jul. 8, 2015**

Related U.S. Application Data

(62) Division of application No. 29/448,177, filed on Mar.
11, 2013, now Pat. No. Des. 756,437.

(57) **CLAIM**

The ornamental design for a monitoring camera, as shown and described.

DESCRIPTION

FIG. 1 is a top, front, right perspective view of a monitoring camera in accordance with our design;

FIG. 2 is a top plan view thereof;

FIG. 3 is a right side elevational view thereof;

FIG. 4 is a left side elevational view thereof;

FIG. 5 is a front elevational view thereof;

FIG. 6 is a rear elevational view thereof; and,

FIG. 7 is a bottom view thereof.

The broken lines depict portions of a monitoring camera in which the design is embodied and form no part of the claimed design.

1 Claim, 4 Drawing Sheets
